(57) **CLAIM**

The ornamental design for a faucet cartridge, as shown and described.

DESCRIPTION

FIG. 1 is a perspective view of a faucet cartridge of the new design;

FIG. 2 is a front elevational view of the faucet cartridge of FIG. 1, the rear elevational view being a mirror image thereof; FIG. 3 is a left side elevational view of the faucet cartridge of FIG. 1, the right side elevational view being a mirror image thereof; and,

FIG. 4 is a top plan view of the faucet cartridge of FIG. 1. The broken lines shown in the figures are included for the purpose of illustrating portions of the faucet cartridge and form no part of the claimed design.

1 Claim, 3 Drawing Sheets
